(57) **CLAIM**

We claim the ornamental design for electronic game design, as shown and described.

DESCRIPTION

FIG. 1 is a perspective view of an electronic game design showing our new design;

FIG. 2 is a top plan view thereof;

FIG. 3 is a front elevational view thereof;

FIG. 4 is a rear elevational view thereof;

FIG. 5 is a side elevational view thereof;

FIG. 6 is a side elevational view thereof, opposite to FIG. 5; and,

FIG. 7 is a bottom plan view thereof.

The broken lines are for illustrative purpose only and form no part of the claimed design.
